UNITED STATES PATENT OFFICE

ARTHUR R. SELDEN, OF ROCHESTER, NEW YORK

MACHINE FOR BANDING A STRIP AND CUTTING THE LATTER BETWEEN THE BANDS
TO PROVIDE BANDED PIECES

Application filed July 15, 1926. Serial No. 122,626.

The present invention relates to a machine for banding a strip and cutting the latter between the bands to provide banded pieces. Another object of the invention is to provide 5 a banding means which will form a band about a moving strip. Still another object of the invention is to provide a band forming means which folds upwardly on opposite sides of a moving strip, the opposite edges of 10 a band forming piece after one edge of the latter has been provided with an adhesive, said means afterwards folding said edges of the band forming piece one upon the other as the band forming piece is carried by the 15 strip through the machine. Still another object of the invention is to wrap about a moving strip a piece of sheet material with an adhesive on one edge so that the two edges of the wrapping material are caused to overlap 20 and adhere one to the other, means being provided which will hold the overlapping edges in cooperative relation during the traveling of the band through the machine until the adhesive has dried. Still another object 25 of the invention is to provide an improved adhesive applying mechanism for a wrapping band. A still further object of the invention is to provide a novel heating means which will dry the adhesive after the wrapping 30 per band has been applied about the moving strip.

To these and other ends, the invention consists of certain parts and combinations of parts, all of which will be hereinafter described: the novel features being pointed out 35 in the appended claims.

In the drawings:

Fig. 1 is a plan view of a machine, constructed in accordance with this invention;

Fig. 2 shows the machine in side elevation;

Fig. 3 is a view of the intake end of the machine with parts in section;

Fig. 4 is a fragmentary transverse section 45 through the machine;

Fig. 5 is a section on the line 5—5, Fig. 6;

Fig. 6 is an enlarged plan view of the parts shown in Fig. 5;

Fig. 7 is a section on the line 7—7, Fig. 5;

Fig. 8 is a section on the line 8—8, Fig. 6; and

Fig. 9 is a fragmentary detail view of the slotted pitman in the adhesive applying mechanism.

In the illustrated embodiment of the invention, 1 indicates a base plate on which is supported a compression tube 2 horizontally arranged and having a flared end 3 through which the material to be banded is passed. The compression tube 2 has two openings 4 at its top wall and two openings 5 in its bottom wall, one in advance of the other. Through these openings 4 and 5 four rotary compression and feeding members 6, 7, 8 and 9 are arranged to operate, the members 6 and 7 being opposite each other adjacent the intake 3 and the members 8 and 9 being opposite each other and being situated at a point farther removed from the intake than the members 6 and 7, so that the two pairs successively operate upon a strip passing through the compression tube 2. The members 6 to 9, inclusive, are preferably in the form of short cylinders with points or projections 9a arranged on their peripheries. The members 6 and 7 are geared together through gears 10 and 11 arranged on their respective shafts and the members 8 and 9 are geared together by gears 12 and 13 having driving connection between them preferably through an idler gear 14 meshing with the two gears 11 and 13. The turning of the combined and compression feeding members 6, 7, 8 and 9 is effected, in this instance, through a bevelled gear 15 on a shaft of the member 9, this bevelled gear 15 meshing with the gear 16 on the shaft 17 extending longitudinally of the machine and having a drive pulley 18 or other suitable driving means connected thereto.

After the material has been compressed by being passed through the compression tube 2, it passes to the band or wrapper applying mechanism. This mechanism embodies, in this instance, a tube 19 forming an extension of the tube 2 and having its discharge end bevelled or cut away at 20. This discharge or bevelled end lies over a slot or opening 21 in a table to which a suitable

band forming piece or sheet is fed, one edge of the piece or sheet preferably having a moist adhesive applied thereto.

With the end in view of shaping or forming the band forming piece or sheet about the compressed strip of material moving through the machine, there is provided a primary forming means which moves the opposite edges of the sheet or strip upwardly on opposite sides of the strip to be banded. This primary forming means, in this instance, is in the form of a roller or wheel 23 mounted to turn on a shaft 24 on a frame 25 which swings on the shaft 26 of the compression and driving member 9. This wheel is grooved and formed with teeth 23a in said groove. It is adapted to operate through the slot 21 in the table 22 beneath the bevelled end 20 of the tube 19. Also mounted on the swinging arm 25 is a pair of forming blades or members 27 which project beyond the periphery of the grooved wheel 23. The wheel 23 is preferably driven through a gear 28 on its shaft meshing with a gear 29 supported on the arm 25 and in turn meshing with a gear 13 on the shaft 26 of the feeding and compression member 9. This primary band forming means is moved toward and from the strip to be banded in any suitable manner. In this instance, a lever 31 pivoted at 32 to a fixed part of the machine and between its ends has one end provided with a roller 33 cooperating with a cam 34 on the shaft 35 on which the compression and feeding member 7 is arranged. The other end of this lever 31 is connected by a link 36 with the swinging member 25, so that when the lever 31 moves in one direction as shown in Fig. 5, it swings the swinging member 25 upwardly to carry the grooved roller 23 and the blades 27 upwardly in order to cooperate with the band or wrapper. Whereas when the lever 31 is moved in the opposite direction, it swings the swinging member 25 downwardly below the table 22 in order that the band forming material may be fed onto the table over the slot 21. Mounted on the swinging member 25 is a holding device in the form of a spring arm 37 which has an edge 38 operable in the slot 21 so as to engage the band forming sheet or material and move it upwardly against the lower edge of the tube 19 adjacent the discharge of the latter and hold the sheet with yielding pressure against said tube so that it does not shift sidewise. Of course, this holder moves downwardly below the slot 21 when the member 25 is swung downwardly with the roller 23.

The band forming material is, in this instance, in the form of paper fed from a roll 39 journaled at 40 to the frame of the machine and passing upwardly from the roller to a feeding mechanism. This feeding mechanism, in this instance, embodies a lower

horizontal roll 41 and an upper horizontal roll 42, the latter being held with adjustable yielding pressure toward the roll 41 by a spring 43. These feeding rolls feed the sheets to the table 22 before mentioned over the slot 21. This feeding, in this instance, is effected through a grooved cam 44 on a sleeve 200 turning on the shaft 17. This cam, in this instance, engages a roller 45 of an arm 46 of a bell crank lever which is pivoted at 47 to the frame of the machine and has an arm 48 extending therefrom and pivotally connected at 49 to a link 50 which is in turn connected at 51 to a swinging member 52 to which a pawl 53 is pivoted, this pawl engaging a ratchet 54 of the shaft 55 of the roll 41 and acting to turn the roll 41 a certain distance when the swinging member 52 is moved in one direction, said pawl riding over the ratchet wheel when the swinging member 52 is moved in the opposite direction. In this way, the feeding roll 41 is given a step by step feeding movement from the continuous movement in the shaft 17. After the sheet has been laid upon or fed to the table 22, a portion thereof is severed from the main portion to provide a band or wrapper. This result may be secured in any suitable manner. In this instance, there is employed a fixed knife 56 the upper edge of which is substantially in the plane of the upper surface of the table 22 and in immediate proximity to said table. A yielding guide plate 57 extends from the feeding roll 41 to said knife 56, this guide plate being opposed by an upper guide plate 58 between which end the plate 57 the material passes. The guide plate 57 extends slightly beyond the edge of the guide plate 58 in order that a movable cutter 59 may cooperate with the fixed cutter 56. This movable cutter is in the form of a vertically movable blade having connected to its opposite ends two guide bars 60 which are vertically reciprocal on cooperating guides on the frame of the machine and are connected at their lower ends by a cross piece 61. This cross piece 61 through an adjusting screw 62 pivotally connects with the lever 31 hereinbefore mentioned so that the reciprocation of the knife 59 may be effected through the lever 31 and consequently in timed relation to the primary folding means, the knife descending and severing a portion of the banding or wrapping material from the main portion after the primary folding means moves below the table 22 and the feeding mechanism for the material operates to feed a portion of the banding or wrapping material over the table at a time between the cutting operation of the knife 59 and the passage of the primary folding means between the table and the knife moving upwardly as the primary folding means moves upwardly.

Before the primary folding means comes into operation, and about the time that the

severing of the band forming piece takes place, an adhesive applying mechanism is brought into operation to apply adhesive to one end of the band forming piece while the latter lies upon the table in a flat condition. 5 This adhesive applying mechanism comprises an adhesive containing tank 63 having an undercut portion at one side, the bottom wall 64 of which is formed with an opening 65 within the tank and above this opening is a roller 66 which receives an adhesive on its surface from a roller 67 also mounted in the container 63, the latter rotating also in engagement with the periphery of a drum 68 10 rotating in container 63. The rollers 66 and 68 rotate by contact with the roller 67 and the latter is operated periodically by a mechanism comprising preferably a ratchet wheel 69 engaged by a ratchet 70 pivotally mounted 15 on a swinging member 71 which turns on the shaft of the ratchet 69. With the member 71 is pivotally connected at 72 a link 73 which in turn is pivotally connected at 74 to an arm 75 which is secured to a rock shaft 76 20 turning on the frame of the machine. The rock shaft 76 also has an arm 201 which is pivoted at 202 to a pitman 203, the latter being slotted at 204 and guided on the shaft 17. This pitman 203 also carries a roller 204 operating on a grooved cam 205 which is secured to the sleeve 200 with the cam 44. 25

The rock shaft 76 also has arms 77 on the opposite sides of the machine connected by an adhesive applier 78 in the form of a metal 30 bar mounted to swing on the two arms 77 about an axis 79, the applying edge 80 of this adhesive applier being eccentric to and operated around said axis. This swinging applier is adapted to have its edge 80 engage 35 one edge of the band material on the table 22 when the applier is in its lower position and when the applier is swung to its upper position, the applying edge 80 passes through the opening 65 in the bottom of the offset 40 portion of the adhesive container to engage with the periphery of the roller 66 in order to receive an adhesive from said surface. Any suitable means may be employed for 45 causing the swinging of the applier 78 on the arms 77. In this instance, at one side of the container and below the offset portion, there is supported on the frame of the machine, an operating device for said applier. This operating device, in this instance, 50 consists of a plate 81 formed with a groove or way 82 in which works a pin 83 on an arm 84 extending laterally from the applier 78, the pin 83 being eccentric to the axis of turning of said applier. As the arms move 55 up and down the pin 83 travels in the way or guide 82. At or about the central portion of this way or guide, there is provided an off set portion 85 into which the pin 83 is 60 deflected as shown in Fig. 4, so that the arms 65 77 move downwardly from the uppermost

position where the applier is projected upwardly with reference to the arms. The applier is swung on its axis 79 so that when the arms reach their lowermost positions, the applier will be projected downwardly as illustrated in full lines in Fig. 4, the swinging or turning taking place at the off set portion 85 of the trackway 82. 70

After the primary folding of the band about the bottom and opposite sides of the strip, a secondary folding takes place which causes the turning of the two upstanding edges of the band forming piece over the top of the strip, one in advance of the other, the one with the adhesive being turned last, so that the adhesive thereon may be brought in contact with the portion first turned. This secondary folding mechanism embodies a tube 88 which has a flared intake portion 89 and has its top portion provided with a flared opening, one wall 90 of which is parallel with the line of feed through the machine while the opposite wall 91 is inclined to said line of feed. The wall 91 engages one upstanding edge of the band material and turns it inwardly while the edge 90 permits the other upstanding edge to maintain its upright position. As the band forming material advances with the strip to be banded, the remaining upstanding edge enters a slot 92 which is at an angle to the line of feed opposite to the angle of the wall 91 of the flared portion. The walls of this slot 92 take the remaining upstanding edge of the banding material or that which is coated and turn such edge inwardly in overlapping relation on the edge first turned, so that the banding operation of the strip is completed. In order to facilitate the entrance of the strip of material and the band into the secondary folder, the end 93 of the tube 19 beyond the cut away portion 20 extends into the flared portion 89 of the secondary folder. 95

After the secondary folding and the uniting of the two edges of the band forming piece to form the band about the strip, the band is subjected to a drying and pressure mechanism which applies pressure thereto during the travel of the band for such a period that the drying of the adhesive can take place. During this drying period, the band is operated upon in a manner to assist the feeding of the strip through the feeding machine without, at the same time, acting injuriously on the bands on the strip. The strip with the bands, after leaving the secondary folder, passes over a flat surface 94 formed by the upper side of a bar 95. On opposite sides of this bar are arranged to operate two endless belts 96, these belts being mounted on two idler pulleys 97 turning on vertical axis 98 adjacent the discharge end of the secondary folder and on opposite sides of the line of feed of the strip through the machine. One lap of each belt which is of 100 105 110 115 120 125 130

flat construction is vertically arranged and operates parallel with the side faces of the bar 95 being held in parallel relation thereto by upstanding guide plates 99 arranged on opposite sides of the bar 95 and in spaced relation to the latter. Adjacent the discharge end of the bar, two rollers 100 are mounted to turn about an upright or vertical axis 101 on opposite sides of the line of feed and the 10 belts edge passing beyond the end of the bar 95 pass about these two rollers 100 and are driven thereby, the two shafts 101 having at their lower ends intermeshing gears 102 and one of the shafts 101 of one of the rollers or 15 pulleys having a bevelled gear 103 thereon with which a bevelled gear 104 and a horizontal shaft 105 meshes. This horizontal shaft 105 also carries a gear 106 meshing in turn with a gear 107 on a shaft 17, so that the shaft 20 17 is utilized for driving the two endless belts 96. Automatic take up pulleys 108 cooperate with the belts 96 on the outer faces of the outer lap, these two pulleys each being supported by an arm 109 pivoted at 110, the two 25 arms being connected by a coil spring 111 which maintains the take up pulleys 108 with yielding pressure against the belts. The receiving portions of these belts are such that each band on the strip is engaged by the 30 belts before it passes from the grooved rollers 23 and in this way the bands are insured of moving with the strip to be banded.

To cooperate with the bands at their adhesively secured joints while the bands on the 35 strip are passing through the channel formed by the two belts 96, a series of yielding pressure and heat conducting devices is employed. In this instance, these yielding pressure devices are in the form of metallic spring arms 40 112 curved transversely to conform to the strip and its bands and each being connected by a yielding bend 113 with an attaching arm 114 which is secured to the under side of a heat conducting bar 115 which in turn is supported by brackets 116 above the strip.

Any suitable heating means may be employed for heating the bar 115. In this instance, an electric heating coil (not shown) is arranged within a porcelain tube 115^a supported in contact with the bar 115. It will be seen that these series of pressure devices yield independently and each covers the strip and its bands but a short distance, but one extends in close proximity to the other so that 50 the strip and its band is subjected to a yielding pressure substantially throughout its travel between the two belts 96 and at the same time these pressure devices are heated, thus insuring a quicker drying of the adhesive. The resilient portions 113 facilitate the passage of the strip and its bands beneath the yielding pressure devices, being disposed or deflected in the direction from which the 55 strip is traveling.

60 In order to divide the strip between the

bends thereon a severing mechanism is employed which is active during the travel of the strip and is continuous in its action. In this instance, after the banded strip emerges from the pressure and drying applying means, it passes through a tapered sleeve 117 at the discharge end of which is arranged a fixed knife blade 118. Cooperating with this knife blade is a movable knife blade 119, in this instance, secured to and projecting from a fly wheel 120 which is rigidly secured to the shaft 17. This projecting knife blade on the rotary fly wheel intersects and severs the strip issued from the tapered sleeve 117 at each rotation of the fly wheel and the periphery of the fly wheel is such that it does not interfere with the travel of the strand or strip.

In order to prevent the bands or wrappers being formed and pasted when a strip is not passing through the machine, a controlling means for the sheet feeding mechanism and pasting or adhesive applying mechanism is provided. In this instance this controlling means embodies a controller 206 pivoted at 207 and lying adjacent the feed wheels 8 and 9 in the path of the strip passing through the machine. This controller is pivoted at 208 to a link 209 which is pivoted to a bell crank lever 210, the latter connecting with a sliding clutch member 211 keyed to the shaft 17 to turn with the latter and movable into and out of engagement with a clutch on the sleeve 200 on which are arranged the cams 44 and 205 that control the paper feeding and pasting mechanisms respectively. A spring 212 acts on the bell crank lever 210 to hold the clutch member 211 out of engagement with the sleeve 200 and to hold the controller 206 in the path of the strip being fed through the machine. When the controlling member 211 is held outwardly by a strip passing through the machine, then the clutch member 210 will be held in engagement with the sleeve 200 and the paper feeding and the pasting mechanism will operate.

This machine is designed particularly for banding or wrapping pipe cleaners which embody wires to which are secured cotton bristles. These cleaners are usually arranged in a package surrounded by wrappers or bands near their centers. Prior to this invention these cleaners have been cut from long strands and then have been assembled in packages and banded or wrapped after being cut. According to this invention, a large number of long strands are assembled to provide a strip which is surrounded by the bands during the movement of the strip through the machine, and thereafter the strip is cut between the bands to provide pieces each of which is in the form of a bundle of the pipe cleaners. It is apparent, however, that the invention is not limited to banding pipe cleaners nor in fact to banding a strip embodying a plurality of strands, as the

machine is capable of operating on any strip. In the operation of the invention the strip is fed into the intake end of the compression tube 3 and is first engaged by the feeding wheels 6 and 7 and fed thereby to the feeding wheels 8 and 9 which with the feeding wheels 6 and 7 compress the material and feed it to the band applying mechanism. The wrapping material is taken from the roll 39 and fed step by step over the opening 21 in the table 22, the wrapping sheet being severed by the knives 56 and 59, as a piece of the wrapping sheet is over the opening 21. About the time this severing of the wrapping or banding takes place, an adhesive is applied to one edge of the banding piece by an applicator 78 which moves toward and from the adhesive roll 66 in the container 63. After the adhesive is applied, the grooved roller 23 with the folding blades 27 move upwardly through the opening 21 and cause the banding forming piece to be pressed into engagement with the strip to be banded or wrapped and at the same time its opposite edges to be drawn upwardly on opposite sides of the strip to be banded or wrapped as shown on opposite sides of Fig. 4 of the drawings. Before the banding piece passes out of engagement with the roller 23, it is engaged by the first finger 112 and the belts 96 so that it is insured of travelling with the strip. The fingers 112 heat the adhesive and dry the same so that by the time the banding pieces pass out of engagement with the belts 96 it is effectively secured about the strip. The strip then is passed to the cutting mechanism where it is severed between the bands.

What I claim as my invention and desire to secure by Letters Patent is:

40 1. A machine of the class described comprising means for moving a strip of material through the machine, means for applying bands to the strip at spaced points while it is in motion through the machine, and means 45 for severing the strip between said bands while the strip is moving.

2. A machine of the class described comprising means for moving the strip through the machine, a support for a flat band forming piece situated to one side of the strip moving through the machine and holding said piece in the stationary position out of engagement with the strip, folding means for moving the opposite edges of said band forming piece 55 on opposite sides of the strip and to cause the band forming piece to engage the strip so as to travel with the latter, and means for folding the edges of the band forming piece one upon the other about the strip as the band forming piece with the strip moves away from the first mentioned folding means.

3. A machine of the class described comprising means for feeding a strip through the machine, a support for a band forming piece situated to one side of the strip moving

through the machine and holding said piece in the stationary position out of engagement with the strip during the movement of the latter, a primary folding means for the folding of a band forming piece on opposite sides of the strip, means for causing said band forming piece to travel with the strip, and a second folding means operating on the opposite edges of the band forming piece after the latter has passed from the first mentioned folding means to cause one of the edges of the band forming piece to overlap the other edge. 75

4. A machine of the class described comprising means for feeding a strip through the machine, a roller for moving a band forming piece into engagement with the strip to cause the band piece to travel with the strip, devices on opposite sides of a roller for moving the opposite edges of the band forming piece on opposite sides of the strip, and a folding means acting on the edges of the band forming piece to cause one to overlap the other. 80

5. A machine of the class described comprising means for feeding a strip through the machine, a table on which a band forming piece is positioned, said table having an opening adjacent the strip being fed through the machine, a roller movable through said opening to cause the band forming piece to cooperate with the strip being fed through the machine in order that the band forming piece may travel with the strip, means movable through said opening for folding the opposite edges of the band forming piece on opposite sides of the strip as the band forming piece is moved into engagement with the strip, and means for folding the opposite edges of the band forming piece one upon the other after the band forming piece with the strip has passed beyond the first mentioned folding means. 95

6. A machine of the class described comprising means for feeding a strip through the machine, means for supporting a band forming piece to one side of a strip passing through the machine, a roller movable toward and from the strip to cause the band forming piece to travel with the strip, blades arranged on opposite sides of and movable with said roller to cooperate with the band forming piece in order to fold opposite edges of the latter on opposite sides of the strip, and means for turning one edge of the band forming piece over the other edge of said band forming piece after the latter has passed the blades. 100

7. A machine of the class described comprising means for feeding a strip through the machine, means for supporting a band forming piece to one side of the strip, and a grooved roller movable to engage said band forming piece to move the latter into engagement with the strip. 110

8. A machine of the class described comprising means for feeding a strip through the machine, means for supporting a band form-

ing piece to one side of the strip, a grooved roller movable to engage said band forming piece to move the latter into engagement with the strip, and mechanism for turning said grooved roller at a speed substantially equal to the travel of the strip through the machine.

9. A machine of the class described comprising means for feeding a strip through the machine, means for feeding a band forming piece into engagement with one side of the strip, two blades for engaging the band forming piece to move the latter on opposite sides of the strip, and means for turning the opposite edges of the band forming piece one upon the other after the band forming piece has passed said blades.

10. A machine of the class described comprising means for feeding a strip through the machine, means for supporting a band forming piece to one side of the path of travel of said strip, a grooved roller movable toward and from the strip to carry the band forming piece into engagement with the strip, a movable support for said roller, two blades carried by said support and arranged on opposite sides of said roller to cooperate with opposite edges of the band forming piece in order to deflect the latter on the side of the band forming piece, and means for folding the edges of the band forming piece one upon the other after the band forming piece has passed with the strip from the blades.

11. A machine of the class described comprising means for feeding the strip through the machine, means for supporting a band forming piece to one side of the path of travel of the strip in a stationary position out of engagement with the strip while the latter is moving, a folding mechanism operating periodically during the travel of the strip to operate on the band forming piece on the supporting means to fold the same partially about the strip, means acting on said band forming piece to cause the latter to travel with the strip after such folding, and a second folding device acting on the band forming piece to fold the edges thereof one upon the other while said piece is moving with the strip.

12. A machine of the class described comprising means for feeding a strip through the machine, means for supporting the band forming piece to one side of the path of travel of the strip in a stationary position and out of engagement with the strip while the latter is moving, folding means for cooperating with a band forming piece on the supporting means for folding opposite edges of the band forming piece on opposite sides of a strip passing through the machine, and a folding tube through which the strip and the band forming piece pass, said tube having a slot formed with walls shaped to fold the

edges of the band forming piece one upon the other.

13. A machine of the class described comprising means for feeding a strip through the machine, means for supporting a band forming piece to one side of the path of travel of the strip in a stationary position and out of engagement with the strip while the latter is moving, folding means for folding a band forming piece on the support about the strip during the travel of the latter, and means for applying an adhesive to one edge of the band forming piece while the latter is on the support.

14. A machine of the class described comprising means for feeding a strip through the machine, a support to one side of the strip passing through the machine on which a band forming piece is adapted to be positioned, means for applying an adhesive to the band forming piece while it is upon the support, and means for moving the band forming piece from the support to the strip, and means for folding the band forming piece about the strip to cause the edge of the band forming piece with the adhesive to be brought into engagement with the other edge of the band forming piece.

15. A machine of the class described comprising means for feeding a strip through the machine, means for supporting a band forming piece to one side of the path of travel of the strip in a stationary position and out of engagement with the strip while the latter is moving, an adhesive container, an adhesive applicer movable from the adhesive container to the supporting means for the band forming piece to apply an adhesive on one edge of a band forming piece on said support, means for moving the band forming piece to the strip, and folding means for folding the band forming piece about the strip to cause the edge with the adhesive thereon to adhere to the other edge of the band forming piece.

16. A machine of the class described comprising means for feeding a strip through the machine, means for supporting a band forming piece to one side of the path of travel of the strip in a stationary position and out of engagement with the strip while the latter is moving, an adhesive container, an adhesive affixer, carrying means for the adhesive affixer for moving the latter from the adhesive container to the supporting means for the band forming piece, and means for imparting a swinging movement to said adhesive affixer as it is moved from the container to the supporting means for the band forming piece.

17. In combination with a means for supporting a wrapper, mechanism for applying an adhesive to one edge of the wrapper comprising a container for an adhesive having an opening and a roller in the container ex-

posed through the opening, an adhesive affixer, carrying-means for moving the adhesive affixer from the container to the supporting means and on which the affixer is pivotally mounted, and a guide fixed relatively to the container for controlling the movement of the affixer on the carrying-means and formed to cause the affixer to pass through the opening and engage said roller at one end of its movement and to apply the adhesive to the wrapper on the supporting means at the other end of the movement.

18. In combination with means for supporting a wrapper, a container having an off-set portion provided with an opening, a pair of swinging arms, an affixer pivotally mounted on said arms and having a projection eccentric to the pivot thereof, and a way on which said projection travels so as to swing the affixer on the arms as the arms carry the affixer from the roller in the container to a wrapper on the supporting means.

19. A machine of the class described comprising means for feeding a strip through the machine, means for supporting a band forming piece to one side of the path of travel of the strip, means for feeding a sheet of material to the supporting means, severing means for cutting the material to provide a band forming piece, means for applying an adhesive to an edge of the band forming piece, means for moving the band forming piece to the strip moving through the machine, and means for folding the band forming piece about the strip as it moves through the machine.

20. The combination with means for supporting a wrapper, means for feeding a sheet of material to said supporting means from one side thereof, means adjacent said side for severing said sheet to form a wrapping piece, and means for applying an adhesive to one edge of the wrapping piece.

21. A machine of the class described comprising means for feeding a strip through the machine, means for supporting a band forming piece to one side of the path of travel of the strip, means for feeding a sheet of band forming material to the supporting means, means for cutting the band forming material to provide a band forming piece, means for applying an adhesive to one edge of the band forming piece, means for folding the band forming piece about the strip during the travel of the latter, a controlling device for cooperating with the strip during the travel of the latter through the machine, and connection between said controlling device and the adhesive applying machine and also between said controlling device and the sheet feeding means so that the operation of both cease when a strip is not being moved through the machine.

22. A machine of the class described comprising means for feeding a strip through

the machine, means for supporting a band forming piece to one side of the path of travel of the strip, means for feeding a sheet of band forming material to the supporting means, severing mechanism for operating upon said sheet to cut a band forming piece therefrom, a grooved roller for moving the band forming piece from the supporting means to the strip passing through the machine, and a lever having connection with the grooved roller and also with the severing mechanism so that the severing mechanism is operated as the grooved roller moves away from the strip.

23. A machine of the class described comprising means for feeding a strip through the machine, means for supplying a wrapping piece with an adhesive along one edge, means for folding said wrapping piece around said strip as the strip passes through the machine to overlap the edges of the wrapping piece, a plurality of yielding devices successively operating on said overlapped edges to maintain their overlapped relation until said adhesive has dried, and means for heating said yielding devices to facilitate the drying of said pieces.

24. A machine of the class described comprising means for feeding a strip through the machine, means for supplying wrapping pieces each with an adhesive along one edge, means for folding said wrapping pieces in spaced relation about said strip as the strip passes through the machine to overlap the edges of the wrapping pieces, and a plurality of heated resilient means successively engaging said overlapped edges for maintaining their overlapped relation until the adhesive has dried.

25. A machine of the class described comprising means for feeding a strip through the machine, means for supplying a wrapping piece with an adhesive along one edge, means for folding said wrapping piece around one edge as the strip passes through the machine to overlap the edges of the wrapping piece, a plurality of arms successively operating on said overlapped edges, yielding portions each secured to the receiving end of said arms to yieldingly support said arms, a bar of high heat conductivity to which said yielding portions are secured, and means for heating said bar.

26. A machine of the class described comprising means for feeding a strip through the machine, means for supplying one at a time wrapping pieces, each with an adhesive along one edge, means for folding the wrapping piece about the strip in spaced relation to each other as the strip passes through the machine to overlap the edges of the wrapping pieces, a bar over which said strip with the wrapping pieces pass, two endless belts operating on opposite sides of the bar to feed the strip with the wrapping pieces, and means

cooperating with the overlapped edges of the wrapping pieces as the strip passes between the belts to hold said edges in overlapped relation.

- 5 27. A machine of the class described comprising means for moving a strip through the machine, a support for a flat band forming piece situated to one side of a strip moving through the machine, a roller for moving the 10 band forming piece from the support into engagement with the strip to cause the band forming piece to travel with the strip, means for moving the opposite edges of the band forming piece on opposite sides of the strip, 15 a folding means acting on the edges of the band forming piece to cause one to overlap the other, and a drying means having feeding elements associated therewith for engaging the band forming piece before the latter has 20 passed out of engagement with the roller.

28. A machine of the class described comprising means for feeding a strip through the machine, a support for a flat band forming piece situated to one side of the strip moving 25 through the machine, a roller for moving the band forming piece from the support into engagement with the strip, means for folding the band forming piece about the strip, and drying means having associated therewith 30 feeding elements which engage the band while it is being folded about the strip and before it has passed out of engagement with the grooved roller.
